UNITED STATES PATENT OFFICE.

FRANK W. HOLMES, OF CHICAGO, ILLINOIS.

FAN.

Application filed August 5, 1927. Serial No. 210,979.

This invention relates to fans and more particularly to exhaust ventilating fans.

An important object of the invention is to provide a fan which is adapted to project 5 a column of air the velocity of which is substantially constant throughout its cross-sectional area.

A further object is to provide a novel blade which is adapted to project air at a 10 substantially constant velocity throughout its length.

A further object is to provide a blade which is graduated in width and pitch in 15 such a manner as to compensate for the varying linear speeds throughout its length and thus discharge fluid from its inner portions at substantially the same speed as from its outer portions.

A further object is to provide a fan blade 20 having the inner portion thereof projecting in the direction of rotation to intercept a greater quantity of air than will be intercepted by the outer portion of the blade, thus compensating for the varying linear 25 rotational speeds of the inner and outer blade portions.

A further object is to provide a blade which is pitched throughout its length, the 30 pitch of the inner portion of the blade being greater than that of the outer portion to compensate for the differences in linear 35 rotational speeds.

A further object is to provide a fan blade which is convexed throughout its length and 35 width to more efficiently "pocket" the fluid in which it is operating whereby a greater quantity of the fluid will be discharged by a fan of a given size.

A further object is to provide a fan of 40 the character referred to the rear edges of the blades of which are straight and arranged in a plane substantially at right angles to the axis of rotation to effect a more efficient discharge of the fluid.

Other objects and advantages of the 45 invention will become apparent during the course of the following description.

In the drawings I have shown one embodiment of the invention. In this showing,

50 Figure 1 is a rear face view,

Figure 2 is an edge elevation,

Figure 3 is a front face view,

Figure 4 is a detail section on line 4-4 55 of Figure 1, and,

Figure 5 is a similar view on line 5-5 of Figure 1.

Referring to the drawings, the numeral 10 designates a suitable hub adapted to be mounted upon a drive shaft and provided 60 with a plurality of projections 11 to each of which a blade indicated as a whole by the numeral 12 may be attached by rivets or the like 13. In the present instance the blades are indicated as being provided with projections 14 at their inner ends which lie 65 against the rear face of the propeller and are secured thereto by screws 15 passing through a plate 16. While the blades have been described as being formed separate 70 from the hub and attached thereto, it will be apparent that these elements may be made integral if desired.

Each blade is convexed throughout its 75 length and width as indicated in Figures 4 and 5. The radial convexity of each blade is greater at its inner portion as indicated at 17 and progressively decreases toward its outer end, as indicated at 18. The fan is adapted to rotate in the direction of the arrow indicated in Figure 1, and the rear edges of the blades are straight as indicated at 19 and are arranged in a common plane substantially at right angles to the axis of rotation. Thus the air or other fluid may be discharged from the fan in the common 80 plane referred to. The forward edge 20 of each blade is inclined in the direction of rotation whereby the outer portion of each blade increases in width toward its inner end. For substantially half its radial 85 length, the forward edge of each blade projects sharply in the direction of rotation as indicated at 21 to intercept a greater portion 90 of the fluid in which the blade is operated.

The outer edge 22 of each blade is pitched as indicated in Figure 2 and the pitch of the blade gradually increases toward its inner end as indicated at 23.

The operation of the device is as follows:

It will be apparent that any number of blades may be employed, but in practice it is preferred that each fan be provided with four blades as indicated in the drawings. 105 The fan is rotated in the direction of the arrow indicated in Figure 1 and it will be apparent that the projecting forward edges 21, arranged in advance of the other portions of the blades, intercept the greater proportion 110

tion of the fluid in which the fan is operated. As previously stated, the pitch of the inner portion of each blade is greater than that of the outer portion, and the greater width and 5 pitch of the inner portions of the blades serve to compensate for the decreased linear rotative speeds at the inner portions of the blades. The greater radial convexity of each blade occurs adjacent the inner portion 10 thereof, and this portion also is arranged slightly in advance of the remainder of the blade with respect to the direction of travel of the fluid, as indicated in Figure 5. This structure also serves to compensate for the 15 varying linear speeds of the inner and outer portions of the blades. The sharply convexed inner portion of the blades shown in Figure 5 tends to prevent any inward slipping of the fluid from the central portion of 20 the blade resulting from the greater quantity of fluid intercepted thereby, while the radial curvature of the outer portion of each blade in the direction of discharge of the fluid tends to overcome centrifugal force and thus 25 prevent outward slipping of the fluid. The fan resulting from the combination of the various structural features referred to is adapted to operate in such a manner as to discharge a column of fluid substantially 30 parallel to the axis of rotation, the linear speed of the inner portion of the column being substantially equal to that of the outer portion. Eddy currents in the resultant fluid column, which would tend to reduce the 35 velocity of the column are substantially eliminated, by forming the blades with straight rear edges arranged at right angles to the axis of rotation.

The characteristics of the fan, as above 40 outlined, render it particularly adapted for use as a ventilating fan, but it will be apparent that the device also is readily adapted for use as a propeller and possesses a high degree of efficiency due to the direction of 45 discharge of the fluid and the uniform velocity thereof.

It is to be understood that the form of the invention herewith shown and described is 50 to be taken as a preferred example of the same and that various changes in the shape, size and arrangement of parts may be resorted to without departing from the spirit of the invention or the scope of the subjoined claims.

55 I claim:

1. A fan blade comprising a body having its forward face concaved transversely thereof and having its forward edge projecting in the direction of rotation and at the end of 60 the body adjacent the axis of rotation, said

body having its forward face concaved throughout its length with the greatest concavity lying adjacent the inner end of the body.

2. A fan blade comprising a body having 65 its forward face concaved transversely thereof and having its forward edge projecting in the direction of rotation and at the end of the body adjacent the axis of rotation, said body being curved rearwardly for substantially half its radial length and then forwardly to its outer extremity. 70

3. A fan blade comprising a pitched body having its forward face concaved transversely thereof and having its forward edge 75 projecting in the direction of rotation and at the end of the body adjacent the axis of rotation, said body having its forward face concaved throughout its length with the greatest concavity lying adjacent the inner 80 end of the body, the pitch of said body progressively increasing toward its inner end for substantially half its radial length and then sharply increasing to a point adjacent its widest portion. 85

4. A fan blade comprising a pitched body having its forward face concaved transversely thereof and having its forward edge projecting in the direction of rotation and at the end of the body adjacent the axis of rotation, said body being curved rearwardly for substantially half its radial length and then forwardly to its outer extremity, the pitch of said body progressively increasing 90 toward its inner end for substantially half its radial length and then sharply increasing to a point adjacent its widest portion. 95

5. A fan comprising a hub, a plurality of blades carried by said hub, each of said blades having its forward face concaved 100 transversely thereof and having its forward edge projecting in the direction of rotation and at the end of the blade adjacent the axis of rotation, each blade having its forward face concaved throughout its length with the greatest concavity lying adjacent the inner 105 end of the blade.

6. A fan comprising a hub, a plurality of blades carried by said hub, each of said blades having its forward face concaved 110 transversely thereof and having its forward edge projecting in the direction of rotation and at the end of the blade adjacent the axis of rotation, each blade being curved rearwardly for substantially half its radial 115 length and then forwardly to its outer extremity.

In testimony whereof I affix my signature.

FRANK W. HOLMES.
